ATTORNEY

UNITED STATES PATENT OFFICE.

CHARLES S. LOCKE, OF JOLIET, ILLINOIS.

CHECK-ROWER FOR CORN-PLANTERS.

SPECIFICATION forming part of Letters Patent No. 280,641, dated July 3, 1883.

Application filed April 14, 1883. (No model.)

To all whom it may concern:

Be it known that I, CHARLES S. LOCKE, a citizen of the United States of America, residing at Joliet, in the county of Will and State 5 of Illinois, have invented certain new and useful Improvements in Check-Rowers for Corn-Planters, of which the following is a specification, reference being had therein to the accompanying drawings.

- 10 My invention relates to an attachment for that class of corn-planters in which the slide for the seed-boxes is operated by a cable fastened at each end of the field and having knots at regular intervals engaging with a vibratable member of the planter's attachment, by which reciprocating motion is transmitted to the seed-box slide; and it consists of the novel devices and combinations of devices, hereinafter described and specifically claimed.
- 15 In the accompanying drawings, Figure 1 represents a plan view of the check-row attachment; Fig. 2, a longitudinal vertical section through the center of the same; Fig. 3, an edge view of the attachment; and Fig. 4, a 25 longitudinal section of the connecting-bar.

Corresponding letters in the several figures of the drawings designate like parts.

A denotes the main or bottom plate of the frame of the attachment, consisting of a segmental plate, *a*, that upon its radial ends has projecting strips *b* and *c*, to one end a projecting arm, *d*, and is cast solid with a central bar, *e*, which to one end has lugs *y*, and to its opposite end a pulley, *f*, and stud *g*, for guiding the knotted cable *B*.

Upon strip *b* is fitted the strip *h* of another segmental plate, *C*, and is secured thereon by two dowels, *i*, of strip *h*, fitting into sockets of strip *b*, and by a screw, *j*, that is tapped into 40 strip *b*.

The plates *A* and *C* have each a hub, *Z*, that is concentric with the curve of their segments, and into each of such hubs *Z* is pivotally secured the trunnion *l* of a Y-shaped lever *D* or 45 *D'*, by means of a washer, *m*, secured upon the end of such trunnion by a screw, *n*. The strips *b* and *h* hold the plates *A* and *C* the proper distance apart for the Y-shaped levers *D* *D'* to be separated just far enough for the cable *B* 50 to pass freely between, but to exclude the knots *o* that are formed or secured upon such cable. The pointed forward ends of levers *D*

D' are chamfered, and their trunnions *l* are about one-third of the entire length of such levers distant from that forward end, and are 55 arranged to be central to the line on which the knotted cable *B* is guided through the attachment.

To near its pointed end each lever *D* *D'* has formed a trunnion, *p*, to engage with the eyes 60 of the bifurcated end of connecting-bar *E*, that is made in two halves secured together by dowels and a bolt, *q*. This bar *E*, holds the two levers *D* *D'* in line with each other, and its opposite bifurcated and eyed end is coupled 65 with either of a series of trunnions, *r*, that project from the sides of the end of a lever, *F*. This lever *F* is pivoted upon arm *d* of plate *A* by a fulcrum-bolt, *s*, and its rear end has a series of holes for pivotally coupling a bar or rod at 70 the necessary distance from the fulcrum of such lever, according to the length of stroke desirable for the seed-slide lever.

At about half distance between trunnion *l* and the rear end of lever *D* such lever *D* is provided with a boss for pivotally securing by a screw, *t*, a small roller, *u*. A latch, *G*, is pivoted with one end on a screw, *v*, tapped into the end of plate *C*. This latch, by a leaf-spring, *H*, is depressed to bear upon roller *u*, and has 75 80 inclined edges, that tend to lock the levers *D* *D'*, on either end of their stroke, with sufficient resistance to require a certain amount of side pressure before such levers can be started toward the opposite end of their stroke.

Projecting and flaring guard-lugs *w* are formed to the corners of the rear ends of levers *D* *D'*, that will prevent the knotted cable from leaving its prescribed course.

The plate *A* of this check-rower attachment 90 is secured in proper position upon the middle or either side of the corn-planter frame by bolts passed through holes in strip *c* and through arm *d*, or in another convenient manner, and the lever *F* is to be suitably connected 95 by a rod or bar with the lever or levers that operate the seed-box slides.

The knotted cable *B*, after being anchored to the field, can be readily inserted from the side of strip *c* between the levers *D* *D'*, and 100 then placed between pulley *f* and stud *g* at one end of plate *A*, and between guide-lugs *y* of the other end of plate *A*, when, as the machine is being moved over the field in the direction

indicated by the arrows, a knot, *o*, of such stationary cable will come in contact with the edges of levers *D D'*, and while the cable itself has a free passage through the space between such levers, the knot will have to follow the relatively-angular lines of these levers, thereby creating a side pressure that will overcome the resistance of spring-latch *G*, and will vibrate the levers *D D'* to swing to the opposite end of their stroke, after which movement the knot *o* will have a free passage between guard-lugs *w* and guide-lugs *y*. The levers *D D'* thus having attained their opposite position, the next knot *o* of cable *B* will now be guided to come in contact with the edges of the opposite side of levers *D D'*, which will tend to swing the levers back to their first position, and in this manner successive knots will come in contact alternately with the opposite edges of levers *D D'*, and will vibrate these levers to and fro with intermittent quick strokes. The vibrations of levers *D D'* being imparted to lever *F* by connecting-bar *E*, such lever *F* again, by any suitable connection, is to be coupled with the lever or arm that operates the seed-box valves or slides in a manner that each movement of the levers *D D'* will tend to drop a seed.

With the above device the seed-box slide or valve is thus operated by a quick short stroke, so essential in the correct dropping of corn.

The movements of the attachment are very easy and yet positive. Its construction is very simple and inexpensive, and it has no parts that can readily wear out or break, and when accidentally broken can be easily replaced by a duplicate piece.

These check-rower attachments can be ap-

plied to all styles of corn-planters, and can be made right and left, to be secured to either one 40 or both sides of the machine.

I am aware that a cam composed of two parts, between which the check-row cable passes, and the knots adapted to act on the edges of such cam in alternate order to vibrate the same, is 45 old, and such I do not desire to claim; but

What I claim is—

1. In a check-rower for corn-planters, the **Y**-shaped levers *D D'*, each pivoted independently and axially in line with the other, and each having exteriorly to its forward end a trunnion, *p*, and both levers being coupled to work in conjunction by and to one bifurcated end of a connecting-bar, *E*, the opposite end of which connects with lever *F*, that again is to 55 connect with the seed-box slides, all substantially as and for the purpose set forth.

2. The herein-described check-rower for corn-planters, consisting of base-plate *A*, having cable-guides and cap-plate *C*, the **Y**-shaped 60 levers *D D'*, pivoted between such plates, each independent of and axially in line with the other, and with an open space between, such levers *D D'* having each a trunnion, *p*, to couple with one end of bar *E*, that connects 65 with lever *F*, and lever *D*, having a stud or roller, *u*, engaging with pawl *G*, that is pivoted to cap-plate *C* and is depressed by spring *H*, the whole being constructed and arranged, substantially as described, to operate as specified. 70

In testimony whereof I affix my signature in presence of two witnesses.

CHARLES S. LOCKE.
